UNITED STATES PATENT OFFICE.

GEORGE E. BARNHART, OF PASADENA, CALIFORNIA.

GOLF CLUB.

Application filed November 23, 1926. Serial No. 150,222.

My invention relates to golf clubs, and more particularly to the construction of shafts of golf clubs and the connections thereof with the heads of the golf clubs.

5 The objects of my invention are: first, to provide a golf club shaft which is spirally slotted so that the same will yield torsionally to a considerable degree; second, to provide a golf club shaft which is spirally slotted in 10 such a manner that the same will yield readily when twisted in one direction but will tend to resist twisting in the opposite direction; third, to provide a ferrule for golf clubs which is undercut at its interior to permit 15 diametrical expansion of portions between spiral slots of the spirally slotted, tubular shaft positioned within the ferrule; fourth, to provide a golf club having a tubular ferrule and a spirally slotted, tapered, tubular 20 shaft positioned with its spirally slotted portion within the ferrule and secured at its inner end to the head, the outer end of the ferrule fitting closely, yet movably around the shaft, the spiral flutes being so arranged as 25 to permit longitudinal extension of the shaft relative to the ferrule and also slight clearance of the shaft with respect to the interior surface of the extended end of the ferrule when the shaft is twisted in one direction, 30 and also to permit longitudinal contraction of said shaft when twisted in the opposite direction, the longitudinal contraction of said shaft resulting in tightening of the latter with respect to the interior surface at the 35 extended end of said ferrule; fifth, to provide a spirally slotted shaft for golf clubs which will simultaneously provide ready torsional yielding and longitudinal flexion, as well as resiliency torsionally and longitudinally; sixth, to provide a ferrule for 40 golf club heads which is tubular in construction and provided with relatively thin walls so that the same will yield longitudinally with the shaft extending therein and secured 45 at its end to the head; seventh, to provide a golf club having a shaft-positioning socket, on its head and a shaft mounted with one end within the socket and shiftable relative to the outer end of the latter, said socket 50 being so constructed as to prevent buckling of the shaft at or near the outer end of the socket; eighth, to provide a golf club of this class in which dirt, dust and grit is excluded from the ferrule and the space between the 55 same and the shaft by an elastic sleeve or band extended around both the shaft and

the ferrule at the joint between the same; ninth, to provide as a whole a novelly constructed golf club shaft and novel means of connection thereof with the head of a golf 60 club; and, tenth, to provide a means of this class which is simple and economical of construction, durable and which will not readily deteriorate.

With these and other objects in view as 65 will appear hereinafter, my invention consists of certain novel features of construction, combination and arrangement of parts and portions as will be hereinafter described in detail and particularly set forth in the 70 appended claims, reference being had to the accompanying drawings and to the characters of reference thereon which form a part of this application in which:

Figure 1 is a fragmentary side elevational 75 view of the head end of a metal head golf club incorporating my invention in one form, certain parts and portions thereof being broken away and in section to facilitate the illustration; Fig. 2 is a transverse sectional view through the ferrule and shaft taken on the line 2—2 of Fig. 1; Fig. 3 is a slightly modified form of the ferrule construction of the golf club head adapted for my special 80 shaft, the ferrule being shown in section to facilitate the illustration; Fig. 4 is a similar view thereof, showing the ferrule as a separate member and secured to the head of the club; Fig. 5 is another fragmentary sectional elevational view thereof, showing still 85 another slightly modified form of ferrule construction of my invention; and, Fig. 6 is a fragmentary sectional elevational view of the structure shown in Fig. 1 with an elastic sleeve over the joint between the shaft and 90 the ferrule.

Like characters of reference refer to similar parts and portions throughout the several views of the drawings.

The head 1 of the golf club, shown in Fig. 100 1, is a conventional type of golf club head, but is provided with a special ferrule 2. Said ferrule is tubular and is tapered from its connection with the head to a reduced diameter at its outer end. The shaft, indicated by 3, is also tubular and is preferably made of steel or other suitable metal. Said shaft, as shown, is tapered from its handle end, not shown, to a reduced diameter at the end connected with the head. The small end of the shaft is positioned within the ferrule and the extreme end of the re- 105

duced portion is secured to the shank end of the head to which the ferrule is connected. The method of securing the end of the shaft to the head may vary to suit conditions. As shown, in the drawings, the shank end of the head is provided with an outwardly tapered recess 1^a in which the end of the shaft is positioned. In the recess 1^a and around the end of the shaft, is poured molten brass, or 10 other suitable binder.

The portion of the shaft 3 within the ferrule 2 is provided with a plurality of spiral slots 3^a. The ends of the slots, nearest the end of the shaft, are spaced from said end 15 of the shaft and the opposite ends of said slots are preferably spaced inwardly from the end of the ferrule, as shown. Said slots are preferably left-hand and of considerable pitch. As the ball or other object is struck 20 with the head 1, the portions of the shaft between the spiral slots, or flutes yield readily to the impact in a circular direction providing yielding and resilient force against the ball, or other object. When the ball, or 25 other object, is struck by the head, the portions of the shaft between the spiral flutes expand radially beyond their normal diameter and also permit the shaft to be extended longitudinally relative to the head. 30 To take care of the radial, or transverse expansion of the shaft within the ferrule, the ferrule is undercut between its inner end and a slight distance from its outer end, as indicated by 2^a.

35 The wall of the bore of the ferrule between the undercut portion and the outer end thereof fits closely around the shaft, but when the shaft is extended longitudinally, as mentioned above, slight play is provided 40 between the shaft and the wall of the bore, permitting slight independent flexion of the shaft relative to the ferrule. It will be noted, however, that the wall of the ferrule is relatively thin, particularly at and near 45 its outer end, permitting said portion of the ferrule to flex with the shaft when the latter is flexed beyond the limit permitted by the clearance between the shaft and the ferrule, as stated. Thus the strain on the shaft 50 is reduced to a minimum.

When the head of the club is twisted in the direction opposite to that permitted by the normal blow, the portions of the shaft between the spiral flutes are contracted diametrically and the shaft is contracted in length, permitting the tapered shaft to be tightened against the wall of the bore at the outer end of the ferrule, providing less torsional yielding and resiliency and check- 55 ing the recoil.

It will be here noted that, although a particular type of golf club head is illustrated and a particular metal head referred to, my invention may be applied to other 60 types now in use without deviating from the

spirit of the invention. It will also be noted that, although the ferrule is shown as an integral part of the metal head, the ferrule may be applied as a separate member for repairing conventional clubs.

70 The ferrules, shown in Figs. 3 and 4, are made slightly heavier at their outer ends and therefore do not yield as readily to and in co-operation with the flexion of the shaft. The bores at the outer ends of the ferrules, 75 in Figs. 3 and 4, are tapered outwardly in curved form so as to permit greater longitudinal flexion of the shaft relative to the ferrule. The undercut portions 2^a, in the structures shown in Figs. 3 and 4, permit 80 flexion of the shaft within the ferrule and substantially permit the shaft to be pivoted at the constricted portion 2^b at the inner end of the bore beyond the undercut portion.

85 The structure shown in Fig. 4 is identical with that shown in Fig. 3 except that the ferrule is shown as a separate member and secured to the shank of the head 1, as when repairing conventional golf clubs, the ferrule being secured to the shank of the head 90 in any conventional manner, such as by brazing, welding, or the like.

95 In the modified form of construction, shown in Fig. 5, the ferrule is not undercut, thereby resisting, to a great extent, transverse expansion and limiting the flexibility. The outer end of the bore, in the structure shown in Fig. 5, is also shown outwardly divergent to permit greater independent 100 flexion of the shaft relative to the ferrule.

105 In Fig. 6 of the drawings, I have shown a flexible cap, sleeve, or band 5, around the joint between the outer end of the ferrule and the shaft for excluding dirt, dust and grit from entering the ferrule and lodging 110 between the same and the shaft and thus preventing proper co-action between the same. The sleeve 5 is preferably made of rubber in tapered form and is positioned with its thick end around the end of the ferrule, and the thin or fin end around the shaft. Thus, the shaft is permitted to flex, twist and expand relative to the ferrule and still exclude dirt, dust and grit therefrom. It will be noted that a similar sleeve may be 115 positioned around the joints of the ferrules and shafts shown in Figures 3, 4 and 5, or a cap, or washer may be positioned within the end of the ferrule around the shaft.

120 Though I have shown and described a particular construction, combination and arrangement of parts and portions, and certain modifications thereof, I do not wish to be limited to this particular construction, combination and arrangement, nor to the 125 modifications, but desire to include in the scope of my invention the construction, combination and arrangement substantially as set forth in the appended claims.

130 Having thus described my invention, what

I claim as new and desire to secure by Letters Patent is:

1. A golf club having a shaft provided with spiral slots, and means covering and sealing the whole of the slotted portion of the shaft.

2. A golf club having a tubular shaft provided with slots in its wall, rigid means covering the slotted portion of the shaft, the latter being movable relative to the former, and flexible means sealing the joint between said means and said shaft.

3. A golf club having a ferrule and a shaft secured at one end within and to the inner end of said ferrule, the portion of said shaft within said ferrule being spirally slotted.

4. A golf club having a ferrule and a shaft secured at one end within and to the inner end of said ferrule, the portion of said shaft within said ferrule being provided with spiral slots, said slots being left-hand and of considerable pitch.

5. In a golf club, a head provided with a shaft securing ferrule, and a tubular shaft secured at one end within and to the inner end of said ferrule, said shaft being provided at the portion within the ferrule with spirally arranged slots.

6. In a golf club, a head provided with a shaft securing ferrule, and a tubular shaft secured at one end within and to the inner end of said ferrule, said shaft being provided at the portion within the ferrule with spirally arranged slots, said slots being left-hand and of considerable pitch.

7. In a golf club, a head having a tubular ferrule, the portion of the ferrule secured to the head being of larger outer diameter and tapered to a small diameter at the end of said ferrule, and a shaft positioned within said ferrule and secured at the extreme end thereof to said head, the portion of said shaft within said ferrule being spirally slotted and readily capable of yielding longitudinally, said shaft being also adapted to be flexed longitudinally with said ferrule.

8. In a golf club, a head provided with a ferrule, and a tapered, tubular shaft positioned with its small end within said ferrule and secured at said end to said head, the portion of said shaft within said ferrule being provided with spiral slots.

9. In a golf club, a head provided with a tubular ferrule, and a tubular shaft extending into said ferrule and secured at one end in said ferrule being spirally slotted and the portion of said ferrule around the spirally slotted portion of said shaft being undercut to permit transverse expansion of said shaft.

10. In a golf club, a head having a socket, a shaft secured at one end within said socket, the portion of the shaft within the outer end of the socket being movable relative to the latter, and a flexible sealing member positioned at the joint between the outer end portion of said socket and said shaft.

11. In a golf club, a head provided with a ferrule, and a tubular shaft positioned with its one end in said ferrule and secured at said end therein, said shaft being provided at the portion within the ferrule with spirally arranged slots.

12. In a golf club, a head, a shaft secured thereto, and means on said head for engaging said shaft a slight distance from the end secured to the head, said means providing a bearing portion for said shaft, the portion of the shaft between its secured end and said means being spirally slotted.

13. In a golf club, a head having a tubular metal ferrule, the portion of the ferrule secured to the head being of larger outside diameter and tapered to a small diameter at the end of the ferrule, the outer portion of the ferrule being relatively thin walled and the extreme end having a thin edge, the interior walls thereof being undercut at a distance inwardly from the upper end of the ferrule, and a metal shaft positioned with one end in said ferrule and secured at said end to said head, said shaft engaging directly the wall of the bore of the ferrule at the normally upper end thereof, the outer end of said ferrule being capable of being flexed with the flexion of said shaft.

14. In a golf club, a head having a metal ferrule of relatively thin walls, and a metal shaft secured at one end within said ferrule, the interior walls of the ferrule being undercut at a distance inwardly from the upper end of the ferrule, said shaft engaging directly the wall of the bore of the ferrule at the normally upper end thereof, said ferrule being capable of ready longitudinal flexion with said shaft.

In testimony whereof, I have hereunto set my hand at Los Angeles, California, this 9th day of November, 1926.

GEORGE E. BARNHART.

In testimony whereof, I have hereunto set my hand at Los Angeles, California, this 110th day of November, 1926.

NOVEMBER, 1923.

I claim as new and desire to secure by Letters Patent is:

1. A golf club having a shaft provided with spiral slots, and means covering and sealing the whole of the slotted portion of the shaft.
2. A golf club having a tubular shaft provided with slots in its wall, rigid means covering the slotted portion of the shaft, the latter being movable relative to the former, and flexible means sealing the joint between said means and said shaft.
3. A golf club having a ferrule and a shaft secured at one end within and to the inner end of said ferrule, the portion of said shaft within said ferrule being spirally slotted.
4. A golf club having a ferrule and a shaft secured at one end within and to the inner end of said ferrule, the portion of said shaft within said ferrule being provided with spiral slots, said slots being left-hand and of considerable pitch.
5. In a golf club, a head provided with a shaft securing ferrule, and a tubular shaft secured at one end within and to the inner end of said ferrule, said shaft being provided at the portion within the ferrule with spirally arranged slots.
6. In a golf club, a head provided with a shaft securing ferrule, and a tubular shaft secured at one end within and to the inner end of said ferrule, said shaft being provided at the portion within the ferrule with spirally arranged slots, said slots being left-hand and of considerable pitch.
7. In a golf club, a head having a tubular ferrule, the portion of the ferrule secured to the head being of larger outer diameter and tapered to a small diameter at the end of said ferrule, and a shaft positioned within said ferrule and secured at the extreme end thereof to said head, the portion of said shaft within said ferrule being spirally slotted and readily capable of yielding longitudinally, said shaft being also adapted to be flexed longitudinally with said ferrule.
8. In a golf club, a head provided with a ferrule, and a tapered, tubular shaft positioned with its small end within said ferrule and secured at said end to said head, the portion of said shaft within said ferrule being provided with spiral slots.
9. In a golf club, a head provided with a tubular ferrule, and a tubular shaft extending into said ferrule and secured at one end to said head, the portion of said shaft within said ferrule being spirally slotted and the portion of said shaft within said ferrule being spirally slotted and the portion of said ferrule around the spirally slotted portion of said shaft being undercut to permit transverse expansion of said shaft.
10. In a golf club, a head having a socket, a shaft secured at one end within said socket, the portion of the shaft within the outer end of the socket being movable relative to the latter, and a flexible sealing member positioned at the joint between the outer end portion of said socket and said shaft.
11. In a golf club, a head provided with a ferrule, and a tubular shaft positioned with its one end in said ferrule and secured at said end therein, said shaft being provided at the portion within the ferrule with spirally arranged slots.
12. In a golf club, a head, a shaft secured thereto, and means on said head for engaging said shaft a slight distance from the end secured to the head, said means providing a bearing portion for said shaft, the portion of the shaft between its secured end and said means being spirally slotted.
13. In a golf club, a head having a tubular metal ferrule, the portion of the ferrule secured to the head being of larger outside diameter and tapered to a small diameter at the end of the ferrule, the outer portion of the ferrule being relatively thin walled and the extreme end having a thin edge, the interior walls thereof being undercut at a distance inwardly from the upper end of the ferrule, and a metal shaft positioned with one end in said ferrule and secured at said end to said head, said shaft engaging directly the wall of the bore of the ferrule at the normally upper end thereof, the outer end of said ferrule being capable of being flexed with the flexion of said shaft.
14. In a golf club, a head having a metal ferrule of relatively thin walls, and a metal shaft secured at one end within said ferrule, the interior walls of the ferrule being undercut at a distance inwardly from the upper end of the ferrule, said shaft engaging directly the wall of the bore of the ferrule at the normally upper end thereof, said ferrule being capable of ready longitudinal flexion with said shaft.

In testimony whereof, I have hereunto set my hand at Los Angeles, California, this 9th day of November, 1926.
